WATER SLED

Charles F. Boucher, 1761 12th St., Santa Monica, Calif.

Filed Feb. 26, 1962, Ser. No. 68,973

Term of patent 14 years

(Cl. D71—1)

FIG. 1.

FIG. 2.

FIG. 3.

FIG. 4.

FIG. 5.

FIGURE 1 is a top plan view of a water sled, showing my new design;

FIGURE 2 is a side elevational view thereof, the opposite side having substantially the same appearance;

FIGURE 3 is a bottom plan view thereof;

FIGURE 4 is a front elevational view thereof; and,
FIGURE 5 is a rear elevational view thereof.

I claim:

The ornamental design for a water sled, substantially as shown.
